MOLDED RUBBER SHOE SOLE

Norman Everett Bovay, Naugatuck, Conn., assignor to United States Rubber Company, New York, N. Y., a corporation of New Jersey

Application February 23, 1950, Serial No. 8,081

Term of patent 14 years

(Cl. D7—5)

To all whom it may concern:

Be it known that I, Norman Everett Bovay, a citizen of the United States, residing at Naugatuck, in the county of New Haven and State of Connecticut, have invented a new, original, and ornamental Design for Molded Rubber Shoe Sole, of which the following is a specification, reference being had to the accompanying drawing, forming part thereof.

Fig. 1 is a bottom plan view of a molded rubber shoe sole, showing my new design; and

Fig. 2 is longitudinal sectional view of the same taken on line 2—2 of Fig. 1.

I claim:

The ornamental design for a molded rubber shoe sole, as shown.

NORMAN EVERETT BOVAY.
